UNITED STATES PATENT OFFICE.

FRANK I. ELLICK, OF OMAHA, NEBRASKA.

LEAF-BINDING CLASP.

1,105,025.

Specification of Letters Patent.

Patented July 28, 1914.

Application filed April 6, 1914. Serial No. 829,763.

To all whom it may concern:

Be it known that I, FRANK I. ELLICK, a citizen of the United States, residing at Omaha, in the county of Douglas and State 5 of Nebraska, have invented certain new and useful Improvements in Leaf-Binding Clasps, of which the following is a specification.

This invention relates to an improvement 10 in leaf-binding clasps useful for holding the edges of leaves or sheets in connected relation and particularly useful for this purpose when mounted in the backs of book covers.

The object of the invention is to provide 15 an article for this purpose which may be conveniently and economically manufactured, may be readily adjusted for holding or releasing the leaves, and will be durable in wear.

20 With these objects in view, the invention presents a novel construction, combination and arrangement of parts as described herein and claimed, and as illustrated in the drawing, wherein—

25 Figure 1 is a front view of the clasp. Fig. 2 is a transverse section thereof on line 2 2 of Fig. 1. Fig. 3 is a transverse section on line 3 3 of Fig. 4, the view being broken and on an enlarged scale. Fig. 4 is a plan view 30 showing open book covers with a pair of clasps applied thereto for holding the sheets or leaves.

Referring now to the drawing for a more 35 particular description, the clasp best shown in Figs. 1 and 2 consists of an angular frame or stationary part 5 and a latch bar 6 pivotally mounted thereon as indicated at 7. The frame 5 may be constructed of an integral, rectangular, elongated, metallic sheet or 40 plate without waste of material or use of solder, said plate being bent near one of its ends substantially at right angles to provide a rectangular bracket-member or wing 8 and a back 9, the wing being bent inwardly toward the back to provide a flange or rectangular leaf-spring 10 disposed inclinedly with 45 reference to said wing 8, said plate also being bent substantially at right angles near its opposite end to provide a second wing 11 disposed in the plane of wing 8, said wing 11 being bent inwardly to provide a flange or reinforcing-plate *a* adapted to abut upon the back 9 and providing a mounting opposite to the spring-leaf 10 for the pintle or pivot- 50 pin 7.

The latch bar is preferably of cylindrical

form and is provided near one of its ends with an aperture, as plainly shown in Figs. 2 and 3, to receive the pivot pin, and is adapted to have swinging movements so that it may become engaged by or released from the spring-leaf, an aperture 12 being formed in and midway between the ends of said leaf or spring and operating as a catch for said latch bar.

It will be noted that wing 8 has a greater width than wing 11, and that aperture 12 is disposed midway between the longitudinal edges of the leaf-spring, and therefore the latch bar is disposed substantially parallel with the back 9 when it engages within aperture 12, the pivot pin 7 and aperture 12 being equi-distant from said back. This construction is of advantage since it provides a bearing-surface on the leaf-spring outwardly 75 of aperture 12 upon which the convexed end of the latch bar may slide for depressing the spring, and provides a uniform space adjacent to the back 9 for containing the ends of the leaves.

80 In operation, spring 10 may be manually depressed, so that the keeper or latch, may be released therefrom and the leaves 13 best shown in Fig. 3, may be withdrawn, said leaves being provided with apertures *b* within which the latch may engage. The latch bar as plainly shown in the drawing is provided with convexed ends *c* and it is of such a length that only a limited movement of the spring is required to effect its release, and 85 the arrangement of parts is such that the latch can be released only by manually operating the spring. Apertures 14 are preferably formed in the back 9 so that the clasps may be mounted in the back 15 of book 90 covers 16 and this mounting may be effected by use of screws, as shown, or other suitable means. By reference to Figs. 3 and 4 it will be seen that the springs of the clasps are disposed in such a position that they are accessible for causing a release of the leaves. To cause the latches to become caught within the apertures of the springs, they may be 95 conveniently swung inwardly of said leaf-springs and the locking is automatic.

100 Among some of the advantages to be derived by use of the invention, in addition to the features already mentioned, it may be stated that the clasps may be used for holding any package of leaves, maps, charts, 110 photographs or the like, and connecting them in book form, and for this purpose

they are generally employed in pairs, or they may be used for this purpose in connection with book covers as shown in Figs. 3 and 4. They may have any suitable size or proportion and may be constructed of any suitable material, though the best results are attained by using attenuated spring steel sheets for the back and wings.

Having fully described the invention, a further explanation relating to operation is not necessary.

What I claim and desire to secure by Letters Patent is,—

1. In a leaf holding clasp, a frame consisting of a rectangular, elongated, integral plate bent at right angles near one of its ends to provide a back and a first rectangular wing having an apertured, inwardly-projecting, inclined flange terminating near said back to provide a spring, said plate also being bent at right angles in the same direction near its opposite end to provide a second rectangular wing having an inturned part adapted to abut upon said back, and a latch bar mounted on the second wing adapted to have swinging movements for alternately entering and leaving the aperture of the inclined flange of the first wing.
2. In a leaf holding clasp, a frame consisting of a rectangular plate bent at right angles near one of its ends to provide a back and a first wing having an apertured inturned part disposed inclinedly with reference to said first wing to provide a leaf-spring, said plate also being bent at right angles in the same direction near its opposite end to provide a second wing having an inturned part to provide a mounting for a pivot-pin, and a latch bar mounted on said

pivot-pin adapted to engage in the aperture 40 of said leaf-spring, and to have a swinging movement for a release from said aperture when the leaf-spring is depressed.

3. In a leaf-holding clasp, a frame consisting of a metallic plate bent near one of its ends to provide a back and a first outwardly projecting wing having an apertured inturned part disposed inclinedly with reference to said first wing to provide a leaf-spring, said plate also being bent in 50 the same direction near its opposite end to provide a second wing having an inturned part to provide a reinforcing plate and to provide a mounting for a pivot-pin, and a latch bar mounted on the pivot-pin for depressing the leaf-spring and engaging in 55 said aperture during one of its swinging movements.

4. In a leaf holding clasp, a frame, comprising a rectangular apertured back, an outwardly-projecting bracket-member connected with one end of the back and having an inturned resilient part provided with an aperture, an outwardly-projecting wing connected with the opposite end of the back, and a cylindrical latch-bar pivotally mounted 65 at one of its ends on said outwardly-projecting wing for engagement of its opposite end with and to depress the inturned resilient part of said bracket-member for permitting 70 said latch-bar to engage within said aperture.

In testimony whereof, I have affixed my signature in presence of two witnesses.

FRANK I. ELLICK.
